UNITED STATES PATENT OFFICE.

JOSEPH S. WILLIAMS, OF RIVERTON, NEW JERSEY.

PIER OR WHARF.

1,317,606.

Specification of Letters Patent. Patented Sept. 30, 1919.

Original application filed December 7, 1906, Serial No. 346,774. Divided and this application filed January 6, 1913, Serial No. 740,354. Renewed June 12, 1919. Serial No. 303,773.

To all whom it may concern:

Be it known that I, JOSEPH S. WILLIAMS, a citizen of the United States, residing at Riverton, in the county of Burlington, State 5 of New Jersey, have invented a new and useful Pier or Wharf, of which the following is a specification.

In a copending application filed by me on December 7th, 1906, Serial No. 346,774, I 10 have described and broadly claimed a novel construction of a pier or wharf provided with a desired number of water-proof sub- water line chambers which are adapted to be united with and form a part of a tunnel, 15 subway, surface traffic lines, or broadly a transportation system in communication with waterways and surface traffic lines, and in my present application which is a division of my pending case, Serial No. 346,774, 20 I have described and broadly claimed a novel water-proof subaqueous structure which may serve the purpose of a pier or wharf or be employed for general storage purposes, and especially for products which 25 are to be transported or received by water- ways.

With the above in view my present invention in its broad and generic scope consists of a novel construction of a water-proof 30 structure preferably constructed of reinforced concrete and provided with one or more subwater line chambers, and a novel method of constructing such water-proof structure and forming a communication 35 with waterways, surface lines and subway and tunnel lines.

It further consists of a novel construction of a pier, wharf or dock, novel means for uniting therewith, lines of transportation, 40 such as for example, subway or tunnel lines, and establishing trunk line systems for transportation therethrough and interchangeable relationship between water, rail, subwater, subway and roadway traffic sys- 45 tems.

It further consists of other novel features of construction all as will be hereinafter fully set forth.

For the purpose of illustrating my invention, I have shown in the accompanying drawings one form thereof which is at present preferred by me, since the same will give in practice satisfactory and reliable results, although it is to be understood that 55 the various instrumentalities of which my

invention consists can be variously arranged and organized and that my invention is not limited to the precise arrangement and organization of these instrumentalities as herein shown and described. 60

Figure 1 represents a sectional plan view of a dock or pier embodying my invention, the same being shown in connection with a subway line and adapted to be connected with a subaqueous tunnel line. 65

Fig. 2 represents a sectional elevation of my novel pier or wharf.

Fig. 3 represents a sectional plan view of a portion of the construction.

Fig. 4 represents a sectional plan view 70 showing a portion of the pier or dock structure united with a subaqueous tunnel.

Fig. 5 represents in section, an elevation of my novel pier or wharf.

Fig. 6 represents a perspective view of 75 the end of the pier, showing especially the lock gates.

Fig. 7 represents a plan view of a working and alining pier.

Fig. 8 represents a sectional plan view 80 of my pier or wharf, the sections being taken on different horizontal planes.

Fig. 9 represents a sectional elevation of my pier or wharf, showing a modified form 85 of construction which may be employed if desired.

Fig. 10 represents a perspective view, partly in section, showing on a larger scale a tunnel section and the wharf during certain stages of construction. 90

Similar numerals of reference indicate corresponding parts in the figures.

Referring to the drawings:

In order to more clearly set forth my novel construction of pier or wharf I will 95 describe the different operations which are employed in building the water-proof structure in the natural or logical sequence in which they take place. It is to be understood that my present construction is preferably built in such a manner that subaqueous tunnel structures or sections may be constructed therein, and the pier or wharf construction may be provided with lock gates or removable closures. One or more 100 subwater line water-proof chambers are provided having means of communication with the wharf floor which latter is provided with a superstructure of any desired nature.

1 designates the longitudinal center line 110

of a surveyed tunnel line having the lines 3—3 parallel therewith and equidistant therefrom, said lines representing the exact structural width of a tunnel line.

- 5 4—4 designate two lines parallel with the center line and equidistant therefrom, such lines being located outside of the lines 3—3 and representing the approximate alining lines for the establishing of guide pilings
- 10 5—5 of the alining piers, as seen in Figs. 4 and 7. According to these lines I establish the alining members 17—17, 18—18 and between and along the same, grade line resistances 2 and alining and supporting piers or
- 15 cradles 85 on defined section lines 6, 19, 9 and 10 and alining parts 11—11 to coöperate with guide bars 12, see Fig. 4, in order to provide for first securing accurate and rapid construction and guiding the tunnel
- 20 sections along the dredged and if desired ballasted and graded tunnel line bed between the approximate alining pilings 5—5 on both sides thereof and under the working platform 7, established on or over the piers, and
- 25 ultimately provide for the easy and accurate placement of the tunnel sections upon fixed pier or cradle carrying grade line supports 2, provided along the line at fixed distances apart below said platform 7 according to
- 30 the predetermined grade of the tunnel line and in accurate longitudinal and sectional alinement.

After establishing the lines in accordance with which the tunnel structure is to be constructed and established and piers and fixed grade line resistances are to be established, with provision for such lines passing through the pier or dock at a desired point, I establish a double row or rows of sheet, 35 interlocking metal or other piling 101—102 around the pier or dock area to the necessary depth to provide for securing a stable foundation. Such double rows of piling 101—102 are at such distances apart as will define the 40 thickness of the concrete or concrete reinforced wall to be afterward established between such rows of pilings.

103 designates a passageway in the water end of the dock area in cases in which a sub-aqueous tunnel line is to be constructed and combined therewith, it being noted that lock gates 104 are established in any suitable manner, said gates being adapted to open outwardly and provide a passage way extending from the floor 105 of the subaqueous chamber of the dock or pier to the top or wharf floor line 106 of the pier.

In order to establish a stable foundation under such area which includes the foundation area of the passageway and extending to the outer piling line 101, wood or concrete pilings 114 may be established in the bottom and such pilings are capped with concrete or cement 117 over the entire area and in an 60 65 intimate contact with the inner surface of

the encompassing wall 107, extending around the chamber of the dock and on both sides of the passageway 103. When such foundation bed is provided and prior thereto, if desired, the inner row of piling 102 is cut away, 70 as shown in Figs. 2, 5, and 9 in order that the capping material 117 on the pilings 114 will be carried into intimate contact with the inner surface of the wall 107 over the entire area and so that subsequent water 75 proofing of the foundation may be carried up the inner surface of the wall 107.

The concrete capping 117 is then covered over the entire area of the piling 114 and into intimate contact with the encompassing 80 wall 107 with one or more layers of asphaltum or other water proofing 119 in order to insure a water tight covering over said capping 117 and if desired in addition to the asphaltum, water proof paper, felt, canvas, 85 open-work metal or other fabric may be placed under the same or between one or more layers thereof and extend over the entire area of the capping 117 and into intimate contact with the vertical wall 121 of 90 the passageway 103, it being understood that the water proofing material 119 is so applied that it will be in intimate contact and water tight union with the grade capping 117.

The vertical water proofing 119 extends 95 upwardly to a sufficient height to provide for laying the full depth of the foundation floor 105 above the capping 117, as hereinafter described or the water proofing 119 may be carried up to the top on the inside of the 100 vertical walls 107 and 121 to the water proofing on the wharf flooring 106. A grid-iron system of I-beams or other metal bars 115 are then placed on the water proof foundation over its entire area so as to extend 105 to the opposite sides and ends of the foundation flooring 105 and the passageway 103 to establish a definite area unit of reinforcement in and over such bed.

After the placement of the lower set of 110 such bars or I-beams 115, they are embedded in concrete or cement 118 or both over the entire area, so that they will be in intimate contact with the vertical portion of the water proofing 119 which is placed on the 115 walls 121 of the tunnel way 103 as well as on the inner surface of the encompassing wall 107.

The embedding material 118 is then leveled and the surface of the entire area covered with one or more layers of water proofing or cement, after which a layer of hot pitch or asphaltum is applied thereto over the entire area with or without using a water proof paper or fabric therewith which is 120 suitably water sealed at the lapping parts so as to cover the entire area and intimately connect the same with the vertical portion of the water proofing 119 which extends on the vertical walls 107 and 121.

Such water proofing material can again be covered with hot pitch and another layer of water proof material or a series of such and one or more layers of such material may 5 be used for the surfacing or finishing coat of asphaltum to cover the entire area and to unite with the vertical water proofing on the inner sides of the surface of the wall 107 of the chamber of the dock and the wall 10 121 of the passageway.

Another set of I-beams or bars 116 are then set on such secondary layer of water proofing of the foundation bed and extend transversely of the lower set 115 or at such 15 angle thereto as may be desired. These are preferably so located as to not only cover the entire foundation 105 of the dock and the lock gate tunnel way but so as to be adapted to be united with the metal framing 20 124 of the vertical walls of the inner lining structure 125, which preferably not only lines the chamber of the dock but also the passageway 103 from the foundation floor 105 to the floor line of the floor 106 25 so that the water proofing between the same and the outer surface of the wall will be continuously supported and reinforced over the entire surface and so that loads on the vertical walls will be distributed with uniformity 30 over the bed and so that the tensile reinforcing element and framing of the flooring will in turn reinforce the vertical framing and walls.

The I-beams or metal bars 116 of the 35 foundation are then embedded in concrete or other suitable material 118 which is again covered with cement and asphaltum or other desired water proofing material by and upon which the working floor can be established 40 over which the rail or transportation system tracks of the tunnel can be laid and passenger and freight platforms 127 and other equipments for a depot established. The inner lining structure 125 provides for supporting and reinforcing the water proofing 45 and for supporting the wharf line floor 106 and the intermediate flooring 128, as well as supporting the foundation floor.

The structural framing of the inner lining 50 structure 125 as best seen in Figs. 1, 3, 9, is shown constructed of vertical I-beams 124 carried up in close proximity to the vertical portion of the water proofing 119, with the I-beam flooring girders 129 of the 55 wharf floor 106 carried across the dock to form a complete roof or covering for the chambers below. The intermediate flooring 128 is then established by connecting the I-beams 130 with the vertical I-beams 124 60 or the girder plates 131 carried thereby.

I have shown the vertical I-beams 124 as resting upon a bed plate 132, which latter rests upon the I-beams 116 or the foundation 65

the supporting girders 129 and 130 of the upper end intermediate flooring 106 and 128 respectively are secured to the vertical I-beams 124 in the usual manner or to angle plates 131, extending across the vertical I-beams 124 and secured thereto in order to support and carry the I-beams 129 and 130. An additional layer of water proofing material such as hot pitch or asphaltum subsequently to the erection of such vertical I-beams of the inner structure 125, can be applied on the surface of the vertical portion of the water proofing 119 so as to fill in any space between the metal of the inner structure 125 and the water proofing 119, thereby producing a better reinforcement of water proofing material. After finishing or facing the surface of the water proofing material with suitable water proofing material as cement or asphaltum, the whole of the vertical framing of the inner structure 125 is embedded in concrete or cement from the foundation floor 105 to the top of the dock or wharf floor 106, it being understood that the ends of the water proofing material 119 are united together. The concrete or cement or other suitable material in which the framing of the inner surface 125 is embedded forms therewith a strongly reinforced concrete, cement or other wall against and in intimate contact with the vertical water proofing from the water proofing in the foundation to the water proofing in the wharf floor and into union with the water proofing on the inner surface of the outer wall 107.

The outer wall 107 may be reinforced by structural metal 108 extending through the concrete of the wall from the top to the bottom thereof or to any desired extent and this structural metal may include I-beams, 105 rods or any other desired forms of such construction. In Figs. 1 and 3 the flooring girders 129 of the wharf floor 106 are shown in plan without the spaces between the same being filled in with concrete, while in Fig. 8 the gridiron flooring bars are shown with some of the bars embedded in the concrete.

Referring now more particularly to Fig. 9, it will be understood that I have shown the respective flooring as being provided with transverse and longitudinally extending reinforcing members or bars, such bars extending into the opposite walls and in the usual manner to plates embedded in the concrete. It will now be apparent that the water proofing of the various foundation and wharf floors are united in such a manner as to envelop the entire subaqueous chamber of the dock or pier construction and the passageway thereof, extending to the end of the outer line of piling 101 so that there can be no leakage into the subaqueous chamber or the pier otherwise than through

the passageway, which will be prevented when such passageway is closed or when the tunnel construction has been sealed therein, as hereinafter described. The outer and inner water proof linings are united by a water proofing material to the vertical water proofing material on both sides of the passageway and the water proofing in the foundation flooring so that a complete water tight union is effected between the tunnel construction when placed in the passageway of the water proofed chamber of the construction.

In order to provide a simple and effectual means for uniting the water proofing of the subaqueous chamber and the water proofing of the passageway, I employ a water proofing material such as asphaltum or cement for embedding the metal I-beams of the flooring under the passageway, as indicated by 134, so that the layers of water proofing extending through the foundation and flooring are connected into a water proof reinforced construction extending from the floor line to the metallic elements 116, which extends along the walls on both sides of the passageway so that the inner and lining structure both of the water proof chamber and the passageway will consist of I-beams or metal bars embedded in the water proof material from the inner surface of the outer wall and from the inner surface of the passageway on both sides thereof and from the water proof flooring of the passageway to the water proofing of the wharf floor.

As seen most clearly in Figs. 1, 2, 4, 6 and 8, the passageway 103 is located in the water area end of the pier and the outer row of sheet metal piling 101 is established across the passageway, as seen in Figs. 1 and 8 and the inner row of pilings are established in order to provide for the increased thickness of wall necessary to give the desired stability and strength for the walls 121 of the lock gate passageway 103, so as to provide for the proper placement and support of the metallic or other framing or carrying members 122, by which the closure gates 104 are supported.

In order to provide the requisite stability for the foundation area of the passageway and to provide for such foundation operating as a grade line pier or support for the tunnel construction the area under the pier is excavated and the foundation area is driven with piling, which is capped with concrete as in the construction of a grade line pier or the foundation flooring 105, as hereinbefore explained. The elements of grade reinforcing members and the water proofing of the flooring foundations of the different chambers of the dock are extended to unite with water proof flooring in the passageway on the outer piling 101 over the

entire width of the passageway 103 so that 65 the water proofing of the flooring of the passageway 103 will be in intimate contact or union with the inner surface of the vertical walls of the passageway. The vertical water proofing of such walls may be supported and 70 reinforced by extending the lining and reinforcing wall or structure 125 of the main chamber to cover and reinforce the water proofing on the inner surface of the outer side walls 121 of the passageway 103, as best 75 seen in Fig. 8. By such means the lock gate passageway and the foundation 105 will be enveloped from the wharf flooring 106 down to and under the subwater line chamber by an unbroken and uniform protection of 80 water proofing reinforced by the lining structure 125 and by the horizontal capping and reinforcing parts of the flooring or foundation structure 105 which may be built up and embedded in water proof material. 85

In order to prevent leakage into the passageway through the material of the inner structure or terminal ends or parts of such inner structure, a filling of water proof material such as cement or asphaltum or 90 both are used in the sides of the foundation of the passageway throughout its length or in the parts thereof back of the closure gates 104 and such water proof material may be reinforced by metal bars or beams similar to 95 those employed for the inner lining structure. Such water proof and reinforced parts as indicated at 137 and 134 in Fig. 8 are in intimate and direct connection with and practically form a part of the water 100 proofing which envelops the chamber and the passageway 103.

156 represents a tunnel structure which has been constructed within the chamber and in line for being floated through the 105 passageway 103 provided with the lock gate 104 or other means employed for opening and closing the same. The grade line of the floor 105 is adapted to be on the tunnel grade line 115 which extends to the grade of 110 the pier line resistances 2.

It will now be understood that when it is desired to float the tunnel structures completed within the water proof chamber, that the outer row of pilings 101 as shown across 115 the end of the passageway 103 in Figs. 1 and 8 between the lines 154 and 155 are cut away on a line with or below the surface of the passageway foundation flooring. Water is admitted into the water proof chamber 120 so that the tunnel sections 156 and 157 may be floated out into their proper location after the means of closure 104 of the passageway 103 have been actuated. The passage 103 is provided with suitable means 11 125 so as to hold a tunnel section in proper sectional alignment by means of bars 12 or otherwise, as the same is lowered into po-

sition on the foundation bed 151. The vertical side framing or lock gate supporting members 122, seen in Figs. 1 and 8 are connected with a distancing head piece or 5 platform 123, see Fig. 6, and a similar or equivalent framing member may be employed at the bottom of the passageway 103 to secure the vertical members in proper relation, such passageway framing having a 10 portion thereof nearest to the passageway 103 embedded in or coated with the water proof material of the alining and reinforcing walls of the inner structure 125. The walls of the inner structure 125 are 15 shown at 136 extending from the dock chamber and along both sides of the passage 103 over and upon the reinforced water proof foundation 105 in close proximity to or in contact with the outer walls of the water 20 proofing thereon, as indicated at 137. The walls 136 on both sides of the passageway 103 are constructed of metal reinforcements embedded in suitable water proofing material, such as asphaltum or cement or a 25 combination of such materials along both sides of the passageway 103.

The tunnel structure is placed in the passageway so that the inner end thereof will extend beyond the section line 6, see 30 Fig. 4. The inner and outer ends of the passageway 103 are then closed in any desired manner to form a chamber adapted to be filled with concrete or other material to establish a continuity of the outer wall 107 35 across the passageway 103 with the tunnel structure embedded therein. The space between the tunnel and bottom of such chamber is filled in with water proof material or cement grouting so that the entire 40 tunnel structure is surrounded by material which will close the passageway and firmly unite the tunnel structure therein, it being understood that any desired reinforcements may be employed.

45 After the establishing of the double lines of pilings 101 and 102 to include the passageway 103 a concrete wall 107 is built up therein of such thickness as to provide the necessary resistance against the water pressure and working conditions to which such 50 wall may be subjected.

In order to secure greater stability in such walls the same may be reinforced by structural metal or sets of bars or beams 108 55 extending from the base to the top of the wall, if desired. After such encompassing wall 107 has been built the area encompassed thereby is excavated to the grade of the tunnel line and to such greater depth as may be 60 required to secure the desired stability of the foundation floor 105 of such encompassed area. The structural metal of the metal framing or the reinforced grade walls of the inner structure 125 may extend above 65 the floor 106 as designated by 111 to pro-

vide a framing or supporting wall for the upper structure 110.

In order to compensate for the difference of lateral pressure at different heights in the water proof chamber, I either employ 70 the reinforced walls of the inner structure of such thickness and stability as will compensate for difference in pressure between the bottom and top of the construction with ample factors for safety therein or I provide 75 for such difference of pressure by constructing the inner walls with a gradual increase and stability of lateral resistance from bottom to top, as seen at 160 in Fig. 2 or by 80 constructing the walls of the inner structure of the lower chamber with a greater thickness and stability than the upper portion of the upper chamber. Such differences in stability and resistance may be provided by 85 increasing the thickness of the walls or by increasing the metal reinforcing elements thereof.

As will be clearly apparent from Fig. 5, I provide means of passage communicating with the different chambers of the wharf 90 structure and with the tunnels united therewith such means being shown for purposes of illustration as consisting of the stairs or elevators 174 preferably located on each side of the tunnel structures and leading from 95 the foundation floor of the wharf structures to the wharf floor.

One of the prominent features of my construction is to not only secure absolute stability 100 and resistance against leakage in the pier or dock proper but to provide for connecting and constructing the subaqueous and sub- 105 way line tunnels and passageways and tunnels and the water proof chamber and tunnel line passageway of the pier, whereby such piers or docks will be adapted to serve as extensions or line connections of shore or subaqueous lines or both and as depots without any liability of the leakage of water 110 thereinto. The shore line section of the sub- 115 way 143 is provided with a water proof lining or construction, as at 144, which corresponds to the water proof construction of the passageway 103 and such construction extends from above the water line or shore to the water proof lining of the subaqueous pier or dock with which such water proofing and the other structural or reinforcing elements are united in water proof and reinforced 120 construction.

The shore line or subway is placed between the extension walls 146 of the dock with reinforced water proofing 147 between such walls and the shore line section 143, it 125 being understood that this forms a water proof construction. The end of the shore line tunnel 143 as indicated at 145, is shown extending into union with the structural metal and reinforced water proof wall 148 130

united with 125 of the pier or dock and such shore line tunnel section is in water proof union with the water proof floor 105, as indicated at 149, at which point the water proofing is shown as extending from within the chamber of the pier end and in union with the water proofing of the walls 148 of the inner structure 145 so that the water proofing of the floor and walls will be effectually united with the construction of the pier. The water proof walls 147 are extensions or continuations of the walls 107 and are built upon the water proof floor 149, the construction being similar to that before described with reference to the passageway 103. The water proof walls 147 and 146 are connected with the water proofing 119 of the wharf structure and they may be capped or united by a water proof capping member extending along and over the shore tunnel line on a line with the wharf floor or on any other suitable grade. The water proofing of the shore line section terminates in an increased section 150 of water proofing which unites with the water proofing portions 147 and 148 and the water proof flooring 149, it being understood that such union 150 extends completely around the shore line structure 143 into intimate contact and union with the water proofing 147 and 149 so as to form a water proof union between the subway tunnel and the pier.

In order to provide absolute stability in such shore line extensions from the pier or dock I preferably extend the walls 107 along the subway, as designated at 146 and line the same with reinforcing or alining walls 147, having a standard of resistance adapted to resist the pressure of the water and leakage of the same therethrough and by establishing in union therewith a stable foundation capped with concrete and water proofing I provide a stable construction corresponding to that already described with reference to the foundation flooring 105 of the chamber and the passageway 103.

It will be apparent from the foregoing that my novel pier, dock or wharf construction is primarily designed to provide wharfage and storage facilities along the shores of waterways between the port warden lines and the shore and to provide a means of communication between water transportation systems and subway and surface traffic systems. Any desired number of subwater line chambers may be employed and these may extend for any desired distance toward the shore or along the port warden lines or along the shore lines or into the shore lines, whereby the construction is capable of use in conjunction with jetty wharf systems as well as wharfage systems extending for any desired distance along the shore, and with any extent of desired or subwater line chambers. As clearly seen at the

left-hand bottom portion of Fig. 5, I provide a drainage well 160 having an inner layer of waterproofing 161, which is in waterproof union with the subwater line chamber of the wharf. 70

It will of course be understood that in case subway lines or tunnel lines are not united with the waterproof chambers that the walls of such waterproof subwater line chambers are preferably sealed and that the means of communication therefrom would be through the passageways to the wharf floor thereabove. The passages extending from the chambers preferably extend laterally and may have communication with the surface in any desired manner to provide communication with warehouses or other buildings on the shores. 75

It will be apparent from the foregoing, that in accordance with my present invention, I employ a metal reinforced cementitious construction which forms an airtight chamber, and such construction is covered with cementitious waterproof material, which is in cementitious union therewith. This waterproof material is preferably between the inner and outer surfaces of the walls of the chamber, and has a greater water resistant capacity than the concrete when properly supported by the construction inwardly thereof. I preferably employ means to protect the cementitious waterproof material from injury. 90

It will now be apparent that I have devised a novel and useful construction of a pier or wharf which embodies the features of advantage enumerated as desirable in the statement of the invention and the above description, and while I have, in the present instance, shown and described a preferred embodiment thereof which will give in practice satisfactory and reliable results, it is to be understood that the same is susceptible of modification in various particulars without departing from the spirit or scope of the invention or sacrificing any of its advantages. 100

Having thus described my invention, what I claim as new and desire to secure by Letters Patent, is:— 115

1. A pier or wharf of reinforced concrete having a subwater line chamber with a drainage well communicating with the bottom thereof, and with a unit layer of waterproofing enveloping the walls of said well and chamber, and said wharf having a floor above the water level which is in communication with a navigable waterway. 120

2. A pier or wharf comprising a structural metal framework embedded in concrete and forming a subwater line chamber, having its walls enveloped with a unit layer of waterproofing, in combination with a passageway leading from said chamber and having its walls formed of structural metal embedded 130

in concrete and covered with waterproofing united with said unit layer of waterproofing, and said wharf having a floor above the water level which is in communication with 5 a navigable water-way.

3. A pier or wharf comprising a structural metal framework embedded in concrete and forming a subwater line chamber, having its walls enveloped with a unit layer of 10 waterproofing, in combination with a plurality of passageways leading from said chamber and each of said passageways having its walls formed of structural metal embedded in concrete and covered with waterproofing 15 united with said unit layer of waterproofing, and said wharf having a floor above the water level which is in communication with a navigable water-way.

4. A wharf structure in traffic communication with a water-way and comprising an earth bed reinforced foundation floor below the water line, waterproofed into union with metal reinforced cementitious and waterproof encompassing walls extending to and 25 in watertight union with a metal reinforced cementitious wharf floor above the water line to form a waterproof chamber, with the waterproofed foundation floor and the walls reinforced by an inner structure extending 30 over and into intimate union with the water-

proofing of the chamber and into union with the wharf floor.

5. A wharf comprising a metal reinforced waterproof foundation floor below the water line, a metal reinforced cementitious outer 35 wall having means protecting its outer face and its inner face waterproofed, a metal reinforced cementitious inner wall engaging said waterproof and extending into union with a waterproof wharf floor and forming 40 a metal reinforced waterproof chamber, said wharf floor being in traffic communication with the water-way and means of passage from such chamber to the wharf floor.

6. A wharf comprising a metal reinforced 45 cementitious construction forming a watertight air chamber therein, extending below the water level, and a wharf floor above the water level in traffic communication with a navigable waterway, said construction being 50 covered with cementitious waterproof material in cementitious union therewith, and a watertight traffic subway passage for traffic from shore into said chamber below said wharf floor.
